J. PEGEL.
TABLE COVER.

No. 21,023.

Patented Sept. 1, 1891

UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER.

SPECIFICATION forming part of Design No. 21,023, dated September 1, 1891.

Application filed January 30, 1891. Serial No. 379,707. Term of patent 3½ years.

To all whom it may concern:

Be it known that I, JULIUS PEGEL, a subject of the Emperor of Germany, residing at Philadelphia, in the county of Philadelphia and State of Pennsylvania, have invented a certain new and original Design for a Table-Cover, of which the following is a specification, reference being had therein to the accompanying drawing.

My invention relates to the surface ornamentation of a table-cover; and it consists of the design illustrated in the accompanying photographic drawing. Its leading features are the outer border A, the inner border B, constituting a single border, and the ornamented field center C, with its center-piece C'.

I claim as my invention—

1. The design for a table-cover, substantially as shown and set forth.
2. The design for the border of a table-cover, consisting of parts A and B, substantially as shown and set forth.
3. The design for the center-piece C', substantially as shown and set forth.

In testimony whereof I affix my signature in presence of two witnesses.

JULIUS PEGEL.

Witnesses:

EDWARD BROMLEY,
ADOLPH PETZOLD.
